UNITED STATES PATENT OFFICE.

JOHN V. LUNDSTROM AND KNUD NIELSEN, OF SCHENECTADY, NEW YORK.

AUTOMATIC HIGH-TEMPERATURE-ALARM APPARATUS.

998,252.

Specification of Letters Patent. Patented July 18, 1911.

Application filed February 16, 1910. Serial No. 544,162.

To all whom it may concern:

Be it known that we, JOHN V. LUNDSTROM and KNUD NIELSEN, of whom JOHN V. LUNDSTROM is a subject of the King of Denmark and KNUD NIELSEN is a citizen of the United States, both residing at Schenectady, in the county of Schenectady and State of New York, have invented certain new and useful Improvements in Automatic High-Temperature-Alarm Apparatus, of which the following is a specification.

Our invention relates to automatic high-temperature alarm apparatus, and the object of our invention is to provide a device which may be so arranged that it will sound an alarm when the temperature of a predetermined apartment or particular location in an apartment shall have reached a certain predetermined degree, together with such elements and combinations as are hereinafter more particularly set forth and claimed. We accomplish these objects by means of the mechanism illustrated in the accompanying drawings, in which:

Fig. 1 is a front elevation. Fig. 2 a side elevation. Fig. 3 a cross section along the line X—X on Fig. 1. Fig. 4 a longitudinal section along the line Y—Y on Fig. 3.

Similar letters refer to similar parts throughout the several views.

The plate, A, is mounted in any suitable manner on the side of the wall of an apartment or in any convenient place and has suitably mounted thereon by means of straps, a, a, or in any convenient manner, the tube, B, (preferably glass) provided with a bulb, C, at one end in which tube may be placed mercury, D, or other ingredient suitable for use in a thermometer. Extending into the bulb, C, at the bottom of the tube is a connecting plug, E, which engages the mercury, D, and has, outside of the bulb, C, a contacting head, F, with which the spring contact or switch, G, is electrically connected, by means of the plate, g, to the current-bearing wire, H, which is connected with one of the poles of the electric bell magnet, J, the other pole of the magnet, J, being connected with the battery, K, which will also be connected by wire, k, with the metallic tube, L, as hereinafter more particularly described.

On the top of the tube, B, we place a cap, b, which is formed upon or attached to the tube, e, which is preferably brass and which

carries a wire, M, secured in the end of the tube, L, preferably by insulated contact screw N. We place within the tube, e, a suitable packing and rubber plugs n, n' about the wire, M, as shown in Fig. 4. Enveloping the tube, e, is the metallic tube, L, which reciprocates upon the tube, e, by means of the operation of a pinion, O, and rack, P, the rack being secured to the rear of the tube as shown in Fig. 2, the pinion, O, being mounted on a spindle, p, extending into the plate, A, and having a thumb screw, q, projecting from the side of the plate to operate the same. We also preferably arrange for guiding or supporting the tube, L, when it is raised on the tube, e. We attach the angle arms, f, f, to the plate, A, above the end of the tube, e, which angle arms project into suitable grooves, h, along the edge of the rack, P, at its junction with the surface of the tube, L. Thus the tube, L, when raised by the pinion will be prevented from leaning to one side or the other and the location of the angle arms in reference to the tube may be adjusted to suit the necessities of the case. The metallic tube, L, is closed at its upper end preventing air from entering the tube at that end. The tube, e, is closed at the end thereof which is within the tube, L, and also in lower end of said tube as shown in Fig. 4. The tube, B, is covered closely by the cap, b, on the tube, e. The mercury in the tube, B, is therefore in substantially an air-tight apartment.

Attached to the tube, L, is a pointer, R, which registers with a scale, S, attached to the plate, A. It is apparent that the position of the end of the wire, M, within the tube, B, will be indicated on the scale, S, by the pointer, R, since the wire is attached to the tube, L, and when that tube is moved toward the tube, B, the wire will move toward the bottom of the tube and its relative position therein will be indicated by the pointer attached to the tube, L, on the scale, S. We preferably place on the scale, S, figures extending from zero to one hundred and eighty, for the purpose of indicating respectively the degrees of heat necessary to cause the mercury in the tube, B, to rise and immerse the end of the wire, M, at its position when the pointer registers with the several degrees on the scale. We also place on the plate, A, above the tube, L, a projection, T, which is in the path of the movement of the tube, L, and will act as a stop

to prevent the tube from being moved out of contact with the tube, *e*, therefore preventing its falling and breaking.

The operation of our invention is easily understood. The wire connected with the end of the tube, *L*, being in contact with the wire, *M*, in the tube by means of the insulated contact screw, *N*, leads to the battery, *K*, the battery being in circuit with the bell magnet, *J*, whereby the bell, *U*, may be rung and with the wire, *k*, in contact with the plug *E*, which is immersed with the mercury, *D*, in the tube, *B*. Thus when the mercury, *D*, is raised by the temperature 15 of the room in which it is placed so that it will immerse the end of the wire, *M*, the circuit is completed and the bell is rung.

Our invention is inexpensive in construction, simple in operation and performs the 20 functions required of it in a positive and satisfactory manner. No parts are exposed which are liable to become disadvantageously affected by the action of the elements. It is not cumbersome, takes but 25 little room, is attractive in appearance and is easily adjusted to the circumstances required regarding the amount of heat necessary in order to give an alarm. It may be used not only in case of a fire, but also for 30 the purpose of notifying the office that the temperature of a cold storage or other plant had become too great.

The tube, *B*, is constructed of such size that the mercury will not become separated 35 into particles after it has engaged the wire. When the temperature decreases if the tube is too contracted the mercury is quite likely to become broken up because of the friction between the sides of the glass tube and the 40 wire.

We do not want to limit ourselves to the material of which we construct the various parts of our device, although we have referred to a brass tube, etc., as any suitable 45 material will come within the scope of our invention.

Where we have referred in the specification and claims to mercury, we mean to be understood as including any suitable substance 50 which will readily indicate the changes in temperature and adapted for use in thermometers. We have referred to the use of a bell magnet, but we do not want to limit ourselves to that particular means for 55 giving an alarm. Where we have referred to the term "wire" herein we mean to include not only a wire of one thickness throughout, but, if necessary, differing in diameter.

What we claim as our invention and desire 60 to secure by Letters Patent, is:

1. An automatic device for registering an alarm, comprising a thermometer glass; a metallic tube; a cap on the end of the tube adapted to fit over the end of the thermometer 65 glass; an enveloping tube closed at one

end adapted to reciprocate on said metallic tube; a wire within said metallic tube; a contact for said wire in the closed end of said enveloping tube; a rack on said enveloping tube; a pinion adapted to engage with 70 said rack; a thumb screw connected with said pinion; a connecting plug in said thermometer glass; a spring contact adapted to engage said plug; a pointer attached to said enveloping tube; a scale mounted near said pointer; a battery; wires connecting said battery with said contact in the head of said enveloping tube and with said spring contact; and an alarm device placed in circuit with the battery and said contacts, substantially as described.

2. The combination of a thermometer glass containing an expansible fluid; a metallic tube; a cap on one end of said tube adapted to fit over one end of said glass; an enveloping tube closed at one end adapted to reciprocate on said metallic tube; a wire connected at one end to the closed end of said enveloping tube and extending through said metallic tube into the thermometer 90 glass; a connecting plug inserted in the thermometer glass; a spring contact adapted to engage said plug; a battery; an alarm device; wires connecting said spring contact and said wire in the metallic tube in circuit with the battery and alarm device when the fluid contents of the glass tube engage the wire therein; and a means for indicating the extent of the projection of the wire into the thermometer glass.

3. The combination of a thermometer glass containing an expansible fluid; a metallic tube; a cap on one end of the tube adapted to fit over one end of said glass; an enveloping tube closed at one end adapted to reciprocate on said metallic tube; a wire; a contact for said wire at the closed end of said enveloping tube, said wire extending through said metallic tube into the said glass tube; a metallic plug inserted in said glass tube; a contact for that portion of said plug which is exterior to said tube; an alarm device; a battery; wires connecting said contact adapted to engage said plug and said contact connecting the wire in the metallic tube with the enveloping tube; and a means for indicating the position of the wire in the thermometer glass, substantially as described.

4. The combination of a thermometer 120 glass containing an expansible fluid; a metallic tube adapted to fit onto the end of said thermometer glass; an enveloping tube adapted to reciprocate on said metallic tube; a wire; a contact for said wire at the end of 125 said enveloping tube, said wire extending through said metallic tube into the said thermometer glass; plugs of non-conducting substance in said metallic tube near each end thereof; an electric connecting plug in- 130

serted in said thermometer glass; a contact for said electric connecting plug exterior of said glass; an alarm device; a battery; a means for placing in circuit with said battery the alarm device and each of said contacts; and a means for indicating the position of the wire in the thermometer glass.

5. The combination with a thermometer glass containing expansible fluid of a tube 10 provided with a cap; plugs of non-conducting substance in said tube near each end thereof; the end of said thermometer glass snugly enveloped by said cap; an enveloping tube adapted to reciprocate upon said first 15 mentioned tube; a wire extending through said first mentioned tube and through said plugs therein and into said thermometer

glass; a contact at the end of said enveloping tube with which said wire connects; a means for raising and lowering said enveloping tube, whereby the wire is raised and lowered in the thermometer glass; a means for electrically connecting the contents of said thermometer glass and said wire with a battery; an alarm device in the circuit between said wire and the contents of said thermometer glass.

In testimony whereof we have affixed our signatures in presence of two witnesses.

JOHN V. LUNDSTROM.

KNUD NIELSEN.
